UNITED STATES PATENT OFFICE.

ALFRED A. GLIDDEN, OF WATERTOWN, AND FRANK R. MCKENZIE, OF BRIGHTON, MASSACHUSETTS, ASSIGNEES TO HOOD RUBBER COMPANY, OF WATERTOWN, MASSACHUSETTS, A CORPORATION OF MASSACHUSETTS.

LINING FOR RUBBER BOOTS AND METHOD OF MANUFACTURING.

Application filed July 26, 1927. Serial No. 208,567.

This invention relates to an improved lining for rubber boots and to the method of manufacturing the same.

The object of the invention is to provide a lining for rubber boots, particularly for molded rubber boots, which can be economically and rapidly manufactured and which will form a smooth and durable lining for the rubber boot in which it is molded.

10 The invention consists in the combination and arrangement of parts set forth in the following specification and particularly as pointed out in the claims thereof, and in the method of manufacture therein set forth.

15 Referring to the drawings:

Figure 1 is a perspective view of a leg section of the lining.

Fig. 2 is a perspective view of a tubular knit member from which the foot section of 20 the lining is constructed.

Fig. 3 is a perspective view of the completed foot section with the toe portion thereon.

Fig. 4 is a side elevation of the completed lining.

Like numerals refer to like parts throughout the several views of the drawings.

In the drawings, 5 is a tubular section which is preferably cut off at one end along 30 the dotted line 6, the leg section thus constructed being preferably of knitted fabric and terminating at its lower end in a plane which is inclined upwardly from the back to the front portion of the leg section.

35 Fig. 2 is a perspective view of a tubular member 7, from which the foot section of the lining is manufactured. This tubular member is preferably of knitted fabric and has angular openings 8 and 9 at the opposite ends thereof.

40 To form the tapered foot section 10, illustrated in Fig. 3, the tubular member 7 is cut along the dotted line 11, Fig. 2, to remove the angular opening 9. The side 12 is

45 then brought up to the side 13 of the angular opening 8 and sewed thereto along the line 14, Fig. 3, thus forming the toe portion 15 of the foot section. The angularly cut end 11 of the foot section is then sewed to the 50 angularly cut end 6 of the leg section along the line 16, Fig. 4.

In practice, a tube of the desired diameter is knitted twelve or more feet in length and is then cut into sections to form leg sec-

tions and then trimmed off at an angle 55 along the line 6, as illustrated in Fig. 1. The foot section 10 is constructed as hereinbefore described and attached by sewing along the line 16 to the leg section 5.

While the terms "sewed" and "sewing" 60 have been used in the specification and claims as one manner of attaching the different parts of the lining of this invention together, it is to be understood that the parts may be joined together in any well-known manner, such as looping or other suitable manner, without departing from the spirit of this invention.

We claim:

1. A fabric lining for rubber boots comprising a tubular leg section, and a tapered foot section closed at one end to form a toe by an inclined seam extending partly across the foot section on the upper side thereof, the foot section being sewed at its rear end 75 to the lower end of said leg section.

2. A fabric lining for rubber boots comprising a tubular leg section terminating at its lower end at a plane inclined upwardly from the back to the front portion thereof, and a tapered foot section closed at one end to form a toe by an inclined seam extending partly across the foot section on the upper side thereof, the foot section being sewed at its rear end to the lower end of 80 said leg section.

3. The method of manufacturing a lining for a rubber boot which consists in knitting an elongated tube and cutting the same into sections constituting leg sections, then knitting a tubular member for a foot section having an angular opening at each end thereof and cutting off one end portion of said foot section, including its angular opening, and at an angle to the length of said foot section, then closing the opposite end of said foot section by sewing one side of the angular opening at that end to the other side of that angular opening to form a toe portion, and then sewing the other angularly cut end of the foot portion to one end of one of said leg sections. 95

4. The method of manufacturing a lining for a rubber boot which consists in cutting off one end of a tubular section of fabric at an angle to form a leg section, then knitting a tubular member for a foot section having an angular opening at each end 100 105

thereof and cutting off one end portion of said foot section, including its angular opening, and at an angle to the length of said foot section, then closing the opposite end of said foot section by sewing one side of the angular opening at that end to the other side of that angular opening to form a toe

portion, and then sewing the other angularly cut end of the foot section to the angularly cut end of the leg section.

In testimony whereof we have hereunto set our hands.

ALFRED A. GLIDDEN.
FRANK R. MCKENZIE.
